UNITED STATES PATENT OFFICE.

FREDERICK WILLIAM VICKERY, OF LONDON, ENGLAND.

PAPER-CUTTING MACHINE.

1,173,904.

Specification of Letters Patent. Patented Feb. 29, 1916.

Application filed June 15, 1915. Serial No. 34,187.

To all whom it may concern:

Be it known that I, FREDERICK WILLIAM VICKERY, a subject of the King of Great Britain, residing at London, England, have 5 invented certain new and useful Improvements in Paper-Cutting Machines, of which the following is a specification.

This invention relates to that class of machines for cutting paper and like material 10 from the reel, in which the material is measured by two rollers between which it passes, such rollers being caused to revolve by suitable mechanism connected to an adjustable crank pin on a driving wheel. With such 15 machines only one half of the revolution of the driving wheel is usually utilized for advancing the paper, the cross cut being made by a vertically moving knife during the second half of the revolution.

20 It has been proposed in connection with printing presses operating from reels with a flat printing bed to provide feeding-off or delivery rollers the cutter having two movements for every one revolution of the operating member. In this construction the rotation of the rollers was commenced at various 25 speeds according to the size of sheet being printed. While this mechanism was satisfactory for the work it had to perform, 30 namely feeding off a length already measured by another device, it could not itself independently accurately and satisfactorily measure paper from the reel. Further the cross cut was made by the usual vertically 35 moving knife.

Now the object of my invention is to measure two complete lengths of material of any desired lengths for one revolution of the driving member; each measurement occupying 40 approximately one half of the revolution for any length of measurement, and to provide a mechanism which will employ approximately the same degree of circumferential travel for any length of sheet.

45 The cross cut is made by a revolving knife timed to sever the web during the time the web is stationary, that is while the crank pin is passing the dead centers. Various mechanisms may be employed for insuring this 50 accurate double measurement and cross cutting, but I prefer to connect my measuring rollers through suitable clutches, gears, etc., direct to the adjustable crank pin on the

driving wheel, whereby I obtain an absolutely accurate measurement of any desired 55 length and two lengths for every revolution of the driving wheel, and the speed at which I commence and finish the measurement of each length is approximately the same for any length.

60 My invention will be clearly understood from the following description aided by the annexed drawings which shows four examples of mechanism for carrying my invention into effect.

65 Figure 1 is an elevation of a mechanical clutch device for operating the measuring feed roller and cross cut knife and showing sufficient of a machine to enable my invention to be understood. Fig. 2 is a plan of 70 the mechanical clutch device shown in Fig. 1. Fig. 3 is an elevation of a device for operating the measuring feed roller by racks capable of being moved from one side of the gear wheel on the measuring feed roller to 75 the other, to revolve the measuring feed roller in the same direction at each reciprocating movement of the racks, and showing the cross cut knife and method of operating same. Fig. 4 is a plan of an electrical clutch 80 device for operating the measuring feed roller. Fig. 5 is an elevation of a ratchet and pawl device for operating the measuring feed roller.

85 According to the device shown in Figs. 1 and 2 I provide one end of the feed roller 1 with a toothed wheel 2 which meshes with a toothed wheel 3 on the pressure roller 4 so that the feed roller 1 and the pressure roller 4 are always in gear, the pressure 90 roller being kept on to the feed roller by springs, weights or other means not shown. On the shaft 5 of the feed roller I position a double faced clutch 6 such clutch 6 being held to the axle 5 by a key on the shaft riding in a slot 7 in the clutch 6 so that it will revolve with the shaft 5 and also be capable 95 of sliding along the shaft 5. On the outside of this clutch 6, I loosely position toothed wheels 8, 9 each being provided with a face 100 for engagement with the clutch 6 and I connect each of the wheels 8, 9 with a toothed rod 10, 11 positioned on opposite sides of the shaft 5 and pivoted at 12 to a lug 13 on a driving disk 14, the lug 13 being secured 105 to a screw radially positioned in the driv-

ing disk 14 so that such pivot 12 can be placed at any part between the shaft 15 of the driving disk 14 and the periphery of the driving disk 14 to determine the degree 5 of movement of the rods 10, 11 and in consequence the degree of circumferential movement of the feed roller whereby the feed roller 1 is made into a measuring roller by reason of its movement determining the 10 length of each sheet to be cut. The clutch 6 is provided with a groove 16 in which is positioned one end of a rocking lever 17 this being pivoted at 18 to some part of the frame of the machine (not shown) the other 15 end of the rocking lever 17 entering a double actioned cam 19 fixed on the shaft 15 of the driving disk 14 so that as the driving disk is revolved the cam 19 will operate the rocking lever 17 to put it in gear with either of 20 the wheels 8, 9 alternately during one revolution of the driving disk 14 and when the pivot 12 shaft 15 and shaft 5 are in line, or in other words when the pivot 12 is 25 passing over the dead center which occurs twice during each revolution of the driving disk 14 the cam 19 operates the rocking lever 17 to declutch one wheel and clutch the opposite one. Now the driving disk 14 which is driven from the main drive wheel 30 20 moves in direction of the arrow after the pivot 12 has got over the dead center, shown in Fig. 1, the cam 19 will actuate the rocking lever to place the clutch 6 in gear with the wheel 9, and the rod 11 will during the 35 movement turn the wheel 9 and in consequence of the clutch being in gear with the wheel 9, will also turn the feed roller 1 to feed the paper 21 from the reel 22 to the cross cutting knives 22^a, 23 and just as the 40 pivot 12 is reaching the other dead center the cam 19 will again operate the rocking lever 17 and remove the clutch 6 from the wheel 9 so that the feed roller is not actuated but remains at rest during which time 45 the paper is cut by the knives; but so soon as the pivot 12 has passed over the dead center the cam 19 moves the rocking lever 17 a further distance and clutches it with the wheel 8 and during this half of the revolution 50 of the driving disk 14 the rod 10 pulls on the wheel 8 and this being clutched to the shaft 5 will move the feed roller 1 until the pivot 12 again approaches the dead center, thus I obtain two feeds of paper 55 to the knives during one revolution of the driving disk 14. The rods 10, 11 are held up to the wheels 8, 9 by slings 24, 25 both being pivoted to the axle 5 and provided with rollers 26, 26, 27, 27 against which the 60 backs of the rods 10, 11 have sliding action. The driving disk 14 is provided with teeth, gearing with a wheel 28 the shaft of which is provided with an elliptic gear wheel 29 meshing with an elliptic gear wheel 30 on the axle carrying the revolving cross cut- 65

ting knife 22^a which has action against the fixed knife 23.

31, 31 are nip rollers which are driven at a faster speed than the feed roller 1 to assist in feeding the paper to the knives 70 75 and keeping the paper taut between them and the feed roller 1.

32, 32 are slitters employed only when it is desired to slit the paper into several widths.

33 is a band for carrying the cut sheets from the knives and 34 is a roller to direct the cut sheets on to the band 33. Or instead of employing the above described clutch mechanism I may employ clutches 80

(such as free wheel clutches) on the shaft 5 of the feed roller 1 operating in diverse directions and connect such clutches each with the rods 10, 11 positioned on opposite sides of the feed roller 1 and gearing or 85 having frictional contact with the clutches, the rods 10, 11 being pivoted to the driving disk 14 as before so that one rod during the half revolution of the driving disk will actuate its clutch and cause it to revolve the 90

feed roller to feed the paper, the other rod and clutch riding free, and during the other half of the revolution of the disk the clutch of the first mentioned rod will ride freely 95 over the shaft of the feeding roller while the second mentioned rod, which in the previous half revolution performed no work, will cause its clutch to engage the shaft of the feed roller and move it in the same direction as the previous movement to feed the 100

paper, but during the time the pivot of the rods is passing the dead centers which occur twice in each revolution of the disk, there is no movement of the feed roller and during 105 this time the paper is at rest and the cutting is performed. By this construction the cam 19 and rocking lever 17 may be dispensed with.

According to Fig. 3 the feed roller 1 and pressure roller 4 are geared together and 110 kept in gear as in Fig. 1 but instead of actuating the feed roller by a clutch I affix on the shaft 5 of the feed roller a toothed wheel 56 and on the opposite sides of same I position the racks 10, 11 these being parallel 115

with each other and secured at one end to a cross head 57 having a race 58 in which slides a block 59 to which is connected the adjustable motion pin 12 of the driving disk 14. The racks 10, 11 are connected at their 120 opposite ends by a bar 60 and surrounding the axle 5 is a head 61 inclosing the racks and having an oval shaped hole 62 encircling the axle 5, the head 61 carrying a T shaped 125

guide piece 63 the end of which is pivoted to a stud 65 secured to the frame of the machine outside of the driving disk, such guide piece 63 also passing through a projection 66 on the cross head 57 and clear of the pin 12. To the head 61 I secure a lug 130

67 this being connected to one end of a bent lever 68 pivoted at 69 to the frame of the machine the other end of the bent lever carrying two rollers 70, 70 engaging a cam flange 71 arranged on the driving disk 14 on the opposite side to that of the pin 12. Now as the driving disk 14 is revolved the cam flange 71 at the end of the each stroke of the racks 10, 11 will act upon the bent lever 68 and rock same, and this will move over the racks for one or the other to engage the wheel 56 to drive same during the next motion of the racks, the period of rest while the pin 12 is passing over the dead centers being the same as at Fig. 1. During the revolution of the driving disk 14 the pin actuates the block 59 which slides in the race 58, and through the block causes a reciprocation of the cross head 57 and racks 10, 11 the projection sliding over the piece 63 to keep the racks 10, 11 moving in the proper direction and always with one of the racks engaged with the teeth of the wheel 56 and as the pin 12 arrives at the dead center the cam flange 71 will operate the lever 68 and throw over the racks 10, 11 for the engagement with the other side of the wheel 56 so that the wheel 56 and the roller 1 will always be moved in the same direction. It is understood that with this construction the length of the cuts must be in definite relation to the pitch of the racks. In this construction I prefer that the revolving knife 22^a be geared with the disk 14.

According to Fig. 4 I show a device for operating the double clutch 6 shown in Fig. 1 electrically, and this I effect by securing to the driving disk 14 two contacts 34^a, 35 each being in the form of a segment of a circle and insulated from the driving disk 14. On the shaft 15, I mount two contact wheels 36, 37 these being insulated from the shaft 15 and I position a contact 38 having action on the contacts 34^a, 35 as the disk 14 is revolved, and against the wheels 36, 37 I position contacts 39, 40. I employ electromagnets 41, 42 positioned on each side of an insulated portion of the rocking lever 17 and I connect such magnets and contacts up by wiring with a battery 43 so that as the contact 34^a is passing over the contact 38 the current from the battery is passed through the wire 44 through the magnet 41, wire 45, contact 40, wheel 37, wire 46 which connects the wheel 37 with the contact 34^a, through contacts 34^a, 38 and wire 47 to battery 43, thus energizing the magnet 41 which draws over the rocking lever 17 and then puts the clutch 6 into gear with the wheel 9 as shown, this clutching taking place during one half revolution of the driving disk 14 but during the other half revolution of the driving disk 14 the contact 35 has come into action with the contact 38 and then the current runs from the battery 43 through wire 44 to and through the magnet 42 then by wire 48 to contact 39, wheel 36, wire 50 (which connects the wheel 36 with the contact 35) 38 and wire 47 to battery, this action energizing the magnet 42 and attracting the rocking lever 17 so as to put the clutch into gear with the wheel 8. There is a space between the ends of contacts 34^a, 35 which corresponds with the dead centers of the pivot 12 so that while these spaces are passing over the contact 38 there is no excitation of the magnets consequently the clutch 6 is in the off position in exactly the same manner as in Fig. 1, the operation of the feeding roller being also the same. Or instead of connecting the two rods 10, 11 to clutches I may connect them to links 51, 52, as in Fig. 5, loosely pivoted to the shaft 5 of the feeding roller 1 and looking in opposite directions, these links 51, 52 carrying pawls 53, 54 which engage a ratchet wheel 55 fixed on the axle 5 of the feed roller 1, the pawls 53, 54 being positioned on opposite sides of the ratchet wheel 55 so that as the disk 14 actuates the rods 10, 11 during one half of the revolution, one pawl will engage the ratchet teeth and actuate the feed roller, the other pawl riding free, and on the other half movement of the disk the first mentioned pawl will run free while the other pawl will actuate the feed roller in a similar manner in which the clutches before mentioned actuate the feed roller. With this construction it will be understood that only certain lengths of sheet can be accurately cut *i. e.* when the stroke of the pin 12 corresponds with the pitch of the teeth of the wheel 55.

Instead of employing a ratchet wheel on the feed roller I may employ an ordinary wheel and provide grip pieces on the links which will engage the wheel to move the feed roller by frictional grip in the same manner.

As the distance of movement of the feed roller determines the length of the paper to be cut, to cut different size sheets, I as before stated, pivot the rods 10, 11 to a block 13 which is engaged by a screw, see Fig. 5, radially positioned on the driving disk so that by actuating this screw the pivot of the rods can be positioned at varying distances radially from the axis of the driving disk to vary the amount of movement of the rods and consequently vary the extent of travel of the feeding roller.

In the drawings I have not shown the framework of the machine but it will be understood that such is employed and that the shafts of all the wheels employed are mounted in bearings fixed therein.

What I claim is:

1. In a machine of the character described, a feeding roller for advancing and measuring material, and actuating mech-

4
nism connected with said roller and adjustable for causing the material to be fed at different lengths, said actuating mechanism being adapted to impart two complete forward feeding movements of said roller upon each cycle of operation of said actuating mechanism.

2. In a machine for cutting material, cutting mechanism, a feeding roller for advancing material to the cutting mechanism, actuating mechanism connected to said roller and adjustable for causing the material to be measured at different lengths, and means cooperative with said actuating mechanism for causing two intermittent and complete forward feeding movements of the roller upon each cycle of operation of said actuating mechanism.

3. In a machine for cutting material, cutting mechanism, a feeding roller for advancing material to the cutting mechanism, actuating mechanism connected to said roller and adjustable for causing the material to be measured at different lengths, rotating means for operating said actuating mechanism, and means cooperating with said actuating mechanism for causing two intermittent and complete forward feeding movements of the roller upon each full rotation of said rotating operating means.

4. In a machine for cutting material, cutting mechanism, a feeding roller for advancing and measuring the material to be cut by said cutting mechanism, a rotating member, and means connecting said roller and rotating member for imparting two full forward feeding movements to the former upon each full rotation of the latter, said connecting means having a radially adjustable connection with said member whereby the length of the material to be cut may be varied.

5. In a machine for cutting material, cutting mechanism, a feeding roller for advancing and measuring material to be cut, a rotating member, means connecting said roller and rotating member for imparting two full intermediate forward feeding movements to said roller upon each full rotation of said rotating member, said connecting means having a radially adjustable connection with said rotating member whereby the length of the material to be cut may be varied, and means for operating said cutting means at the intervals between each full rotation of said feeding roller.

6. In a machine of the character described, a pair of rollers for feeding material forward, a driving gear, a shaft, a pair of gear wheels loosely mounted on said shaft, clutch members keyed to said shaft and engageable with said gears, a rack bar for each gear and in mesh therewith, said bars extending on opposite sides of said shaft, means pivotally connecting said bars to said driving wheel whereby said racks are reciprocated,

and means operated from said driving wheel by actuating said clutch members for alternately engaging said gears during one revolution of said wheel, said rollers being operatively connected to said shaft.

70

7. In a machine of the character described, a pair of rollers for feeding the material forward, a shaft having one of said rollers operatively connected thereto, rack bars extending on opposite sides of said shaft, a driving wheel, an adjustable crank connecting said racks with said wheel whereby the former are reciprocated, said connection being adjustable relative to the wheel for varying the length of material fed by said rollers, and means for alternately placing said racks in a positive driving connection with said shaft.

75

8. In a machine of the class described, a feed roller for advancing material, gear means for rotating said roller, a driving wheel adapted to rotate said roller with two full feeding movements to each full rotary movement of the wheel, rack bars adapted to mesh with said gear means at substantially diametrically opposite points and having a crank connection with said wheel whereby said bars are reciprocated, and means for automatically causing said rack bars to effectively operate said feed roller alternately upon each reciprocating movement of said bars.

85

9. In a machine for cutting sheet material, cutting knives, a feed roller for advancing material to said knives and measuring the length thereof to be cut, gear means for rotating said roller, a driving wheel, rack bars adapted to mesh with said gear means at substantially diametrically opposite points and having a crank connection with said wheel whereby said bars are reciprocated, means for automatically causing said bars to effectively operate said feed roller alternately upon each reciprocating movement thereof, each reciprocating movement of the racks effecting a complete and distinct feeding operation of said roller, and means operated from said driving wheel for causing said knives to cut the material between the end and beginning of each reciprocating stroke of said racks.

90

10. In a machine for cutting sheet material, cutting knives, a feed roller for advancing material to said knives and measuring the length thereof to be cut, gear means for rotating said roller, a driving wheel, rack bars adapted to mesh with said gear means at substantially diametrically opposite points and having a crank connection with said wheel whereby said bars are reciprocated, means for automatically causing said bars to effectively operate said feed roller alternately upon each reciprocating movement thereof, each reciprocating movement of the racks effecting a complete and distinct feed-

105

110

115

120

125

130

ing operation of said roller, means operated from said driving wheel for causing said knives to cut the material between the end and beginning of each reciprocating stroke 5 of said racks, and means for adjusting said crank connection whereby the length of material fed is varied.

In testimony whereof I have hereunto set my hand in presence of two subscribing witnesses.

FREDERICK WILLIAM VICKERY.
